[57] CLAIM

The ornamental design for a digital wrist watch, substantially as shown and described.

DESCRIPTION

FIG. 1 is a top right perspective view of a digital wrist watch showing our new design;

FIG. 2 is an end elevation view thereof, the opposite view being substantially a mirror image thereto;

FIG. 3 is a top plan view thereof, the bottom being conventionally plain and unornamented; and

FIG. 4 is a side elevation view thereof, the opposite side being substantially a mirror image thereto.
